FASTENER APPLYING DEVICE

Herman J. Spencer, Ingomar, Pa.

Application April 9, 1953, Serial No. 347,718

6 Claims. (Cl. 1—49)

This invention relates generally to improvements in stapling machines and more particularly to the type of stapling device held and supported in the hand of the operator and actuated by a gripping movement thereof.

One object of the invention is to provide a better means for connecting the driver and its actuating means wherein there will be no chance of the relatively thin driving blade becoming bent during the driving of staples.

Another object of the invention is to provide a pivotally mounted staple support member which is of rigid construction and therefore will give a more positive support as it travels with a staple as the latter is driven.

A further object of the invention is to provide an implement of the type described wherein on manual operation, the jaws are moved to grip the material without the usual necessity of having the hand lever pivot, thereby providing means whereby the jaws can be opened wider for insertion of material and to provide a machine in which longer legged staples can be used.

Other objects of the invention reside in certain novel arrangements of parts which permit access to the upper side of the staple magazine so as to enable the operator to retract the staple feeding means when loading of the device is desired.

A still further object of the invention is to provide a better arrangement of the parts and their relation to each other for reciprocating the driver and for urging the device to grip material to be stapled.

In the accompanying drawings which illustrate a present preferred embodiment of my invention—

Figure 1 is a sectional view in side elevation showing a stapling machine embodying one arrangement of the operating levers in starting position with the driver in raised position;

Figure 2 is a view in side elevation showing the device in Figure 1 with the jaws as having moved towards each other;

Figure 3 is a sectional view taken through Figure 1 at III—III to illustrate the method by which the upper end of the driver blade is secured to a tube type driver head;

Figure 4 is a view in side elevation showing the device in Figure 2 with the jaws completely closed and the driver as having been lowered to drive a staple;

Figure 5 is a cross-section of Figure 2 at V—V to illustrate how the actuating lever rests on an extruded portion of the magazine frame member;

Figure 6 is a plan view of the slotted tube used to retain the driver blade in engagement with the driver head;

Figure 7 is an end view of Figure 6;

Figure 8 is a side elevation of a modified construction shown in Figure 1, illustrating the parts in their starting position with the driver in lowered position relative to the frame member, and with an upper pivoted hand grip member resting on the magazine frame member;

Figure 9 is a view in side elevation showing the device in Figure 8 with the jaws having been moved towards

2

each other and the driver as having been raised in relation to the magazine frame member;

Figure 10 is a front view and Figure 11 is a side elevation view of the rigid type staple support member;

Figure 12 is a plan view and Figure 13 is a side elevation view of the driving blade;

Figure 14 is a front elevation of the machine head and Figure 15 is a sectional side elevation view of Figure 14.

Figure 16 is an enlarged central sectional view of the 10 driver assembly parts shown in Figures 1 and 3;

Figure 17 is a view in side elevation showing the device in Figure 2 with the actuating lever as having been raised upwardly to give access to the staple feeding pusher;

Figure 18 is a partial side elevation of Figure 8 showing 15 the hand-grip part as having been swung from its overlying position over the staple guiding track to a position which gives access to the staple guiding track;

Referring to the drawings, and particularly to Figures 1, 2 and 3, the stapling machine comprises generally 20 a magazine frame member 1 which carries a staple ejection chute at its free end and means for feeding staples to the ejection chute and a reciprocably mounted driver assembly 5 to be described later for ejecting the staples S.

An anvil member 2 carries a staple clinching means 80 25 on its free end, the latter being movable towards the free end of member 1 to grip material there between and to clinch a staple S driven from the ejection chute 8.

A driver actuating lever 3 is connected to rigidly reciprocate the driver assembly 5 and to urge the free end of magazine frame member 1 towards the free end of the anvil member 2 by action of a hand lever 4 pivoted to the anvil member 2 on shaft 43 and through links 6 which connects the hand lever 4 to the actuating lever 3. The magazine frame member 1 and the anvil member 2 are pivoted in relation to each other adjacent their opposite ends by pin 38. See Figures 1, 2 and 4.

The magazine frame member 1 (Fig. 5) is comprised of an elongated U-shaped frame which has a web 9 integral with spaced apart, aligned and upwardly extending side flanges 9a and the latter's one ends are formed towards and in alignment with each other to provide spaced apart transversely extending vertical flanges 10 with the latter's aligned vertically extending edges 10a forming the sidewards walls of the ejection chute 8.

45 The opposite ends of flanges 9a of the magazine frame member 1 are pierced to receive pin 38 and at a point between their ends, flanges 9a have aligned shoulders 41 extending a short distance transversely outwardly to provide a seat for lugs 39 of the actuating lever 3. See Figures 1, 3 and 5.

55 A U-shaped head portion 11 (Figures 14 and 15) has a central web 13 integral with side-portions 12 and the latter at their lower ends are secured to the outward vertical sides of the frame's flanges 9a at a point adjacent the latter's transversely formed flanges 10; side-portions 12 of the head 11 contain aligned closed end elongated slots 26 which extend vertically above the frame's flanges 9a to provide a guide for a driver assembly 5. The lower portions of the sides 12 of the head 11 are formed inwardly towards each other and are spaced apart to form vertical flanges 50 and the latter's rearward surfaces 50a act as the front wall of the ejection chute 8. See Figures 1, 3, 14 and 15.

An elongated U-shaped staple guide 7 has the outside 65 surface of its web 83 secured centrally to the inside surface of the frame's web 9 (see Figure 5) and the upper edges 85 of the vertical flanges 84 of the staple guide 7 form a track upon which the staples S ride in straddle fashion to the ejection chute 8. See Figures 1 and 5. Extending longitudinally, overlying and spaced apart from edges 85 of the staple guide 7 are hold-down members 49, as disclosed in my application No. 305,943,

filed August 23, 1952, and issued as U. S. Letters Patent No. 2,755,473 on July 24, 1956, which are adapted to move transversely from overlying the staple guide 7 to a position which exposes the staple guide for loading or removal of staples. See Figures 1 and 5.

A pulley wheel 14 is mounted on pin 15 which is supported in apertured openings in the flanges 84 of the staple guide 7 at a point near the one end of staple guide 7 which terminates at the ejection chute 8. A feeder spring 16 is passed around pulley 14 and has one end secured to a lug 17 which extends upwardly from the web portion 83 of staple guide 7 and its other end secured to a lug 18 which extends downwardly from the web off the inverted U-shaped staple pusher 19, the latter being urged by the pull of spring 16 to feed the staples S towards the ejection chute 8.

The actuating lever 3 is an elongated inverted U shape, has a web portion 81 used as a hand-grip which is integral with downwardly extending flanges 82. At one of their ends flanges 82 are adapted to be connected to operate the driver assembly 5 and adjacent their opposite ends flanges 82 of the actuating lever 3 have downwardly extending curved lugs 39 for slidably mounting the actuating lever 3 on the magazine frame 1 to urge the latter towards the anvil lever 2. Aligned holes are pierced intermediate the ends of flanges 82 of the actuating lever 3 to receive rivets 45 for connecting links 6 to lever 3. See Figures 1 and 2.

The anvil member 2 is U-shaped in cross-section, it has a web 2a integral with side walls 2b, the latter are pierced at their opposite ends to receive pin 38 and walls 2b are pierced intermediate their ends to receive pin 43. An anvil 80 is secured to the one end of member 2 for clinching a staple and gripping material.

The manually operated hand lever 4 shown in Figure 1 is of channel shape in cross-section with its rearward portion formed with a rounded bottom wall 4b providing a hand-grip and its forward side walls 44 extending upwardly at an angle to adapt them to straddle the sides of the anvil member 2. A cross-pin 43 projects through and beyond holes in the sides 2b of the anvil member 2 and into the side walls 44 of the hand lever 4 for pivotally mounting the latter on the anvil member 2. The upper ends of the side walls 44 are pierced to receive rivets 46 for pivotally connecting lever 4 to the opposite ends of links 6. See Figure 1.

The driver assembly 5 comprises a cylindrical tube-like driver head 23 containing a slot 25 which extends along the length of its diameter and has a hole 24 pierced centrally in its diameter opposite from its slot 25. See Figures 1, 3 and 20. A driving blade retainer 27 is a flexible cylindrical tube containing a slot 30 which extends along the length of its diameter and centrally located along one side of its slot 30 is a lug 29 which protrudes into slot 30. A hole 28 is pierced centrally at a point on the diameter of the driving blade retainer 27 opposite the latter's slot 30. See Figures 6 and 7. A driving blade 20 is preferably made from flat sheet metal, is rectangular in shape, has a centrally located lug 21 extending from one of its short sides and has a hole 22 pierced centrally along its length a short distance from lug 21. See Figures 12, 13 and 20. It will be noted in Figure 3 that the driver head 23 is of greater length than the driving blade retainer 27 for reasons to be explained.

The parts of the driver assembly listed above are assembled together as follows: The outside diameter of the driver head 23 (Fig. 20) is approximately the same as the inside diameter of the flexible driving blade retainer 27. The driver head 23 is inserted inside of the driving blade retainer 27 with their respective slots and centrally located holes in alignment with each other. The driver blade 20 is forcibly inserted flatwise by its lug 21 and into slots 30 of the blade retainer 27 and thereby wedges past the latter's lug 29 to thereby slightly expand the diameter of the blade retainer 27. The blade

20 is moved further, through slot 25 in the driver head 23 until lug 21 of the driver blade 20 is in holes 24 and 28 in the driver head 23 and the blade retainer 27 respectively and lug 21 of the driver blade 20 thereby prevents lengthwise movement between the driver head 23 and the blade retainer 27. See Figure 3. When lug 21 of the driver blade 20 has entered holes 24 and 28 as explained above, the lug 21 end of the driving blade 20 rests against the inside diameter of the driver head 23 and hole 22 of the driver blade 20 is lined up with and receives lug 29 of the blade retainer 27 as the latter springs back to its unsprung diameter. Lug 29 of the blade retainer 27 thereby holds the driver blade 20 in proper alignment relative to the driver head 23. See Figures 1, 3 and 20.

When in the device, the length of the driving blade retainer 27 extends transversely in a horizontal plane between the side portions 12 of the head 11 to be limited thereby from moving transversely in the device. See Figure 3. The driver head 23 extends transversely from the center of the device through and beyond the closed end slots 26 of the side portions 12 to be guided thereby during vertical movement. The portions of the driver head 23 which extend beyond the side portions 12 of the head 11 are entered into openings in flanges 82 of the actuating lever 3 and the latter through its movement thereby reciprocates the driver assembly 5 in relation to the magazine frame member 1 when a fastener is to be applied. See Figures 2, 3 and 4.

30 The manner in which the anvil member 2 and the magazine frame member 1 are moved to grip the material and the assembled driver 5 is lowered in relation to the magazine frame member 1 to secure a staple in the material is shown in Figures 1, 2 and 4 but will be described later.

While the retainer 27 is described as being made from resilient material and containing a lug 29 along one edge protruding into its slot 30 for engagement with hole 22 of the driver blade 20 to retain the latter in engagement with the driver head 23, it will be apparent that a lug similar to lug 29 could be added to the driver head 23 to retain the driver blade 20 in engagement with the driver head 23.

45 The staple support member 31 shown individually in Figures 10 and 11 is preferably made from flat sheet metal. As shown in Figures 1 and 10, the staple support member 31 has its upper end formed into a hook 32, downwardly from its hook 32 and formed forwardly is a bump section 33, slightly below its bump 33 are angled flanges 34 which extend forwardly at a downward angle and still further downward from its angled flanges 34 it has a toe 35 which extends horizontally towards the opposite end of the device. The toe 35 of the staple support member 31 is adapted to fit between the legs to contact and thereby rigidly support the underside of the crown of a staple as the latter is sheared from a stick of staples and thereafter ejected from the device into material.

55 In the starting position shown in Figure 1, the driver assembly 5 is in raised position relative to the magazine frame 1 and a staple S has been fed into the ejection chute 8 slightly beneath the driving blade 20 of the driver assembly 5. The hook 32 of the staple support member 31 is fitted over and extends half-way downwardly around the driving blade 20 of the driver assembly 5 and the toe 35 of the staple support member 31 is between the legs and under the crown of the staple S. The bump section 33 of the staple support member 31 is against the rearward vertically extending side 13a of web 13 of the head member 11

60 to prevent the staple support member 31 from pivoting clockwise on the assembled driver 5 to thereby retain the toe 35 of the staple support member 31 in staple supporting position. See Figure 1.

65 When the driver assembly 5 is moved vertically downward in relation to the magazine frame member 1, the

following results: The driver blade 20 of the driver assembly 5 almost immediately contacts the upper side of the crown of the staple S and urges the latter vertically downward into almost immediate contact with toe 35 of staple support member 31. In the latter position, the driving blade retainer 27 of the driver assembly 5 has moved downwardly slightly way from contact with that portion of hook 32 of the staple support member 31 which was fitted over the driving blade retainer 27. Further downward movement of the driver assembly 5 moves the staple S and thereby the staple support member 31 through the latter's toe 35 vertically downward with the bump section 33 of the staple support member 31 rubbing the vertically extending side 13a of web 13 to thereby hold toe 35 of staple support member 31 in staple supporting position. Note in Figures 4 and 15 that web 13 of head 11 is angled forwardly and downwardly at 13b to provide space into which bump 33 of the staple support member 31 can move to allow the latter to pivot clockwise on the driver assembly 5 as the latter nears the end of its downward movement during the ejection of the staple S. Also note in Figures 4, 14 and 15, that the upper edges 40 of flanges 50 of head 11 are adapted to be contacted by the angled flanges 34 of the staple support member 31 as the latter is moved downwardly to thereby pivot the staple support member 31 in relation to the driver assembly 5. As the driver assembly 5 moves downwardly near the end of its downward movement to eject the staple S, flanges 34 of the staple support member 31 contact edges 40 of flanges 50 of head 11 and thereby pivot the staple support member 31 clockwise in relation to the driver assembly 5 to thereby move toe 35 from its staple supporting position and to move bump 33 into the space provided by the angled end 13b of web 13 of head 11. After toe 35 of staple support member 31 has been moved from its staple supporting position, the driver assembly 5 continues to move a short distance further downwardly to completely eject the crown of the staple S past toe 35. See Figure 4.

As the driver assembly 5 is moved upwardly from the position shown in Figure 4 to that shown in Figure 1, the following takes place: The driver assembly 5 moves upwardly a short distance into contact with that portion of hook 32 of the staple support member 31 which was fitted over the driving blade retainer 27 of the driver assembly 5 and thereby moves the staple support member 31 upwardly. As the staple support member 31 is moved upward, as just described, the latter's bump 33 contacts the angled section 13b of web 13 of head 11 to thereby pivot the staple support member 31 counter-clockwise in relation to the driver assembly 5 to thereby move toe 35 of the staple supporting member 31 into staple supporting position. When the driving blade 20 of the driver assembly 5 has been raised completely to the position shown in Figure 1, the sidewardly extending ends 35a of toe 35 of staple support member 31 are adapted to contact shoulders 36 of flanges 50 of head 11 to stop upward movement of toe 35 of the staple support member 31 to position the latter so a staple S can be fed into the ejection chute 8. See Figures 1, 3, 14 and 15.

Referring to the apparatus shown in Figures 1, 2, 4 and 18: In Figure 1, the starting position, the anvil member 2 and the magazine frame member 1 have their free ends spaced apart with their opposite ends pivoted together by pin 38. The driver assembly 5 is in raised relation in the magazine frame member 1 and a staple S has been fed into the ejection chute 8 beneath the driving blade 20 of the driver assembly 5. One end of the actuating lever 3 is pivotally connected to the driver head 23 of the driver assembly 5 to reciprocate the latter and lugs 39 of the actuating lever 3 are slidably resting on the shoulder portions 41 of the magazine frame member 1 to rigidly urge the latter's free end

towards the free end of the anvil member 2. The hand lever 4 is pivoted on the anvil member 2 intermediate the latter's ends by pin 43 to thereby urge the free end of the anvil member 2 towards the free end of the magazine frame member 1 to grip material and clinch a staple. The side walls 44 of the hand lever 4 extending upwardly along both sides of the device are pivotally connected to the rearwardly positioned ends of links 6 by rivets 46. The forwardly ends of links 6 are pivotally connected to the actuating lever 3 at a point between the latter's ends by rivets 45. Note in Figure 1 that rivets 46 connecting the side walls 44 of the hand lever 4 to the rearwardly ends of links 6 are positioned between pin 38 and rivets 45 close by an imaginary line 10 extending substantially longitudinally of the device through pin 38 and rivets 45. Also note in Figure 1 that pin 43 connecting the hand lever 4 to the anvil member 2 is a distance vertically below the above-mentioned imaginary line and it will be apparent that pressure applied on the hand lever 4 to rotate the latter counter-clockwise on pin 43 will be transmitted in substantially a longitudinal direction along said imaginary line to links 6 and then to the actuating lever 3 through rivets 46 and 45. As longitudinal movement of lever 25 3 and links 6 is not possible nor desired, the hand lever 4 is thereby stopped from rotating counter-clockwise on pin 43. However, manual pressure applied on the hand-grip portion of the actuating lever 3 and the hand lever 4 will bodily move the latter upwardly and thereby the free end of the anvil member 2 through pin 43 is moved upwardly towards the free end of the magazine frame member 1 with rivets 46 moving away from said imaginary line of pressure upwardly in an arc around rivets 45. See Figure 2.

Continued manual pressure on the device after the parts have reached the positions shown in Figure 2 will result as follows: The free end of the anvil member 2 will continue to move as before towards the free end of the magazine frame member 1 until said free ends are 30 stopped by contact with each other or by contact with material placed therebetween. However, when movement of said free ends towards each other is stopped as described above, the hand lever 4 can now rotate counter-clockwise on pin 43 and does so to thereby direct pressure at an angle 35 across said imaginary line to rivets 45 via links 6 and rivets 46 to thereby transmit pressure applied to hand lever 4 to the actuating lever 3 to thereby move the latter downwardly in fastener applying direction. The pressure transmitted to the actuating lever 3 as just described is partly transmitted to the driver assembly 5 to actuate the latter to apply a fastener and the balance of the pressure so applied to lever 3 is transmitted via the latter's lugs 39 to shoulders 41 of the magazine frame member 1 to urge the latter's free end to grip the material. See Figure 4. It will be noted in Figure 4 that during the final movement of the parts as described above, rivets 46 have moved further in an arc around rivets 45 to position the latter between rivets 46 and pin 43 to thereby greatly increase the leverage advantage of the hand lever 4 during the fastener applying operation of the device.

Spring 37 extends vertically and it is positioned rearwardly from pin 38, the latter being the pivot of the magazine frame member 1 with the anvil member 2, spring 37 has one end attached to the rearmost end of the actuating lever 3 and has its other end detachably held by lug 42 of the anvil member 2 to thereby rock the actuating lever 3 on the latter's lugs 39 to move the one end of lever 3 upwardly in relation to the magazine frame member 1 to the limit provided by the driver assembly 5 contacting the uppermost ends of the closed end slots 26 in head 11 of the magazine frame member 1, to thereby retract and thereafter retain the assembled 70 driver 5 in raised relation to member 1 and to urge the

free ends of said magazine frame member 1 and anvil member 2 apart. See Figures 1 and 4.

Notice in Figures 1, 2 and 4 that the anvil member 2 has notches 47 adjacent the pivot pin 38 of the magazine frame member 1 and the anvil member 2 and that projections 48 on the magazine frame member 1 are adapted to contact notches 47 of the anvil member 2 to limit the distance the free ends of the device can move apart.

Figure 18 illustrates the device shown in Figure 1 with the one end of spring 37 as having been removed from lug 42 of the anvil member 2 with the actuating lever 3 as having been pivoted counter-clockwise on the driver assembly 5 to thereby raise the opposite end of the actuating lever 3 in relation to the magazine frame member 1 to thereby expose the latter's staple guiding and feeding means to provide access to the latter.

A modified form of the device is shown in Figures 8 and 9. The magazine frame member 76 and anvil member 77 are pivoted together by pin 90 and said members contain the usual apparatus such as a staple clinching means, a staple driver, staple feeding means, staple ejection chute etc. The driver actuating levers 51, which extend along both sides of the device, are pivoted on the common pivot pin 90 and therefore levers 51 do not transmit pressure to urge either of the members to grip the material. The arms 86 of the hand lever 78, employed in Figure 8, are pivoted to one end of links 54 by rivets 93, links 54 are pivoted at their opposite ends, by rivets 92, to the driver actuating levers 51 to actuate the latter, and slots 52 of the driver actuating levers 51 slidably connect the latter levers to the driver assembly 87 to reciprocate the latter. It will be noted in Figures 8 and 9 that operation of lever 78 will move the anvil arm 77 towards the magazine 1 and that continued movement of lever 78 would lower the actuating levers 51 in a manner similar to the device shown in Figures 1, 2 and 4 to lower the driver. However, to apply pressure on the magazine frame member 76 I employ a hand-grip lever 55 pivoted on pin 90 and it has transversely extending flanges 56 which, in the operative position shown in Figure 8, rest on the upper edges 94 of the side-walls 95 of the magazine frame member 76 at a point between the pivot of the members with each other and the ejection chute end of the magazine frame member 76, for transmitting manual pressure applied on hand-grip lever 55 to the magazine frame member 76, to urge the latter member's free end towards the anvil member 77, to grip one side of material.

Hand-grip lever 55, can be pivoted at least 180° clockwise on pin 90 to move the hand-grip portion of lever 55 from overlying the staple magazine to give access to the latter for retraction of the staple pusher and loading of staples as shown in Figure 18.

In Figure 8, around pin 91 is coiled a spring 58, and has one of its legs 59 pressing against the inside portion of the web of the anvil member 77 and its other leg 60 pressing against the under-side of the magazine frame member 76 for urging the members apart and thereby urging the hand lever 78 to pull links 54 to the starting position shown in Figure 8 after a staple has been driven as explained above.

I claim:

1. In a fastener device, a frame, a staple guide in said frame for guiding staples, a driving channel at one end of said guide, means in said frame for feeding staples along said guide to said driving channel, a staple driver, means mounting said driver for reciprocating movement in said driving channel, a movable rigid staple support member having a toe portion extending toward the other end of said guide into position, between the legs and under the crown of a staple fed into said driving channel, connector means between said driver and said staple support member adapting the latter to pivot and move bodily in relation to said driver and for moving said staple support member in reverse fastener applying direction, means on said frame for limiting said upward movement of said

driver and said staple support member in relation to said frame to thereby retain said staple support member's toe portion in proper position to receive a fed staple, limited guiding means on said frame for engaging said support member to hold the latter's toe portion in staple supporting position under the crown of a staple as said driver moves said staple in fastener applying direction and to thereby move said support member in the fastener applying direction, obstruction means on said frame, cam means on said support member adapted to contact said obstruction means as said support member is moved by said staple and the staple by said driver for pivoting said support member on said driver to shift the toe portion of said staple support member from its staple supporting position, thereby permitting said driver to move relative to said staple support member to complete the driving of said staple, cooperating means between said support member and the end of the latter's limited guide means on said frame for obstructing upward movement of said support member when said driver is retracted upward adjacent to the limit permissible between the latter and said support member, said cooperating means at the end of said guide on said frame adapted to cooperate with said support member to move the latter's toe portion towards the other end of said guide and thereby into staple supporting position as said support member is raised by said driver.

2. In a fastener applying device, a magazine frame member containing a driving channel and means for gripping one side of material at its free end, an anvil member having means for gripping the opposite side of said material and for clinching a staple on its free end, pivotal connector means between said members to permit said free ends of said members to move towards each other to grip material to be stapled, means for feeding staples to said driving channel in said magazine frame member, a staple driver, means mounting said driver for reciprocating movement in said magazine frame member, an actuating lever operably connected to said driver to rigidly reciprocate the latter and shiftable connector means between said actuating lever and one of said members adapted to rigidly transmit a part of the pressure applied on said driver-member actuating lever to one of said members to rigidly urge a free end of one of said members to grip one side of material, a hand lever pivoted on the opposite member for rigidly urging the latter's free end to grip the opposite side of said material, operable connector means between said hand lever and said actuating lever adapted to rigidly transmit pressure applied on said hand lever to said actuating lever at a point intermediate the latter's connections with said driver and said one member to thereby rigidly transmit a part of pressure applied on said hand lever to said actuating lever to urge the latter to rigidly reciprocate said driver and to rigidly move the free end of said one member to grip one side of said material and the balance of the pressure so applied acting to urge the free end of said opposite member to rigidly grip the opposite side of said material.

3. In a stapling machine, a driver head containing a slot on one of its sides which extends along its length, cooperating retaining means including a resilient means on said driver head, a driver blade in said slot, said resilient means acting to retain said driver blade in said slot.

4. In a stapling device, a pivoted magazine frame member containing a driving channel and means for gripping one side of material at its free end, means in said magazine frame member for feeding staples to said driving channel, a staple driver, means mounting said driver for reciprocating movement in said magazine frame member, a pivoted anvil member having means for gripping the opposite side of said material and for clinching a staple on its free end, pivotal connector means between said members adapted to permit at least one of said members' free ends to be moved towards said other's free end to grip said material there between, an actuating lever pivotally connected at one end to said driver to reciprocate the latter and having its opposite end pivotally mounted

on the device adjacent the latter's opposite end, a hand lever pivotally mounted on said anvil member, a link pivotally connected to said hand lever and to said actuating lever with the pivotal connections of said link at the beginning of a fastening operation with the free ends of said members spaced apart being along a line which starts at the pivot of said members with each other and extends substantially across the reciprocating path of said driver and thereby pressure applied on said hand lever at said beginning will not permit said hand lever to rotate in relation to said anvil member but will permit said hand lever to be bodily moved towards said line to thereby move the free end of said anvil member towards the free end of said magazine frame member with the pivot of said link with said hand lever moving away from said line in an arc around said link's pivot with said actuating lever to a position in which continued pressure on said hand lever will be directed through said link through the link's pivotal connections to said actuating lever in a direction which is at an angle across said line to thereby urge said actuating lever to reciprocate said driver to apply a fastener.

5. A stapling device according to claim 4 characterized by means adapted to be held in one hand and wherein said actuating lever has a hand-grip portion which overlies said means for feeding staples, means in the pivotal

20

25

mounting of said opposite end of said actuating lever which permits the latter end to be freely raised upwardly in an arc in relation to said magazine frame member to give access to said staple feeding means.

6. A stapling device according to claim 4 characterized by said hand lever extending below said anvil member to form the lower part of a hand-grip means: an upper hand-grip means overlying said means for feeding staples and it is pivotally mounted by one of its ends on the device's opposite end preferably on the members' pivot, abutment means on said upper hand-grip means adapted to rest loosely against said magazine frame member to transmit pressure applied on said upper hand-grip to said magazine frame member to urge the latter's free end to grip material, said upper hand-grip member adapted thereby to be pivoted to thereby move its abutment away from contact with said magazine frame member and to move it from overlying said staple feeding means to expose the latter.
